UNITED STATES PATENT OFFICE.

ALLEN J. COUGHENOUR, OF FORT LEAVENWORTH, KANSAS.

SHIPPING-CASE.

1,120,792.

Specification of Letters Patent. Patented Dec. 15, 1914.

Application filed January 13, 1914. Serial No. 811,879.

To all whom it may concern:

Be it known that I, ALLEN J. COUGHENOUR, citizen of the United States, residing at Fort Leavenworth, in the county of Leavenworth and State of Kansas, have invented certain new and useful Improvements in Shipping-Cases, of which the following is a specification, reference being had to the accompanying drawings.

10 This invention relates to carriers or receptacles for eggs and similar fragile commodities, the invention having for its principal object to provide a device of this character which is so constructed that all liability of breakage of the eggs or other articles in shipment will be obviated.

The invention has for another of its objects to produce an article carrier of the above character which will yieldingly support a large number of articles within a comparatively restricted space and admit of the rough handling to which such carriers are usually subjected without displacing the articles from their respective positions so 25 that the same will engage or contact with each other.

The invention further has for a general object to materially improve the construction of such carriers or receptacles without 30 greatly complicating the same or enhancing the cost of manufacture thereof.

With the above and other objects in view as will become apparent as the description proceeds, the invention consists in certain 35 constructions, combinations and arrangements of the parts that I shall hereinafter fully describe and claim.

For a full understanding of the invention, reference is to be had to the following description and accompanying drawings, in which—

Figure 1 is a top plan view of an article carrier constructed in accordance with the preferred embodiment of the invention, one 45 of the case or carrier sections being partly broken away; Fig. 2 is a section taken on the line 2—2 of Fig. 1; Fig. 3 is an end elevation showing the carrier sections folded or arranged in superposed relation upon each 50 other; Fig. 4 is a plan view of one of the carrier sections showing a slightly modified form of the invention; Fig. 5 is a section taken on the line 5—5 of Fig. 4; Fig. 6 is a detail fragmentary view illustrating the 55 manner of cutting the felt sheet with which the eggs or other articles directly contact;

Fig. 7 is a detail fragmentary plan view of one corner of a carrier section showing a slightly modified form of the suspension means for the egg receiving frame; Fig. 8 60 is a top plan view of a carrier section disclosing a further modification; Fig. 9 is a section taken on the line 9—9 of Fig. 8; Fig. 10 is a detail vertical section showing a modified construction of the yieldable supporting or suspending means for the article receiving frame; Fig. 11 is an enlarged detail plan view of one corner of the crate section. Fig. 12 is a detail vertical section showing another modification of the yieldable support for the article receiving frame. Fig. 13 is a detail fragmentary vertical section showing a still further modification of the suspension device. Fig. 14 is a detail section of the case. 75

Referring in detail to the drawings, and more particularly to Figs. 1, 2 and 3 thereof, 5 designates two similarly constructed case sections. Each of these case sections includes a rectangular boundary wall 6 and 80 a cover member 7 which is adapted to be arranged upon one end of said boundary wall and secured thereto. This cover consists of a base board 8 upon the edges of which the marginal strips 9 are secured, said base 85 board entirely closing one side of the case section. However, before the cover member 7 is secured in position upon the body wall 6 of the case section, a frame structure for the support of the eggs or other articles is 90 secured to the boundary walls. To this end, I provide in the opposite edges of the ends and sides of the wall 6 suitably spaced notches shown at 10. 11 indicates a wire of the requisite gage which is wound or 95 wrapped upon the wall 6, said wire seating or being fitted into the notches 10. It will be particularly observed from reference to Fig. 2 of the drawings that the adjacent parallel strands of said wire contiguous to one edge of the wall 6 are spaced from each other to a greater extent than the opposite corresponding wire strands on the other edge of said wall. In other words, the latter wire strands are disposed inwardly of the 100 strands first referred to. After the wire has been wrapped in one direction, around the opposed walls of the case section, a wire is wrapped in a similar manner upon the other parallel walls, so that they intersect the first 105 wire strands. These intersecting strands of wire define a plurality of pockets or com-

partments between the boundary walls 6 of the case. A thin resilient metal sheet 12 is then disposed within or between the boundary walls of the case body, and this metal sheet which is preferably of aluminum is slotted or cut as shown at 13 to provide a plurality of series of resilient tongues 14 which are punched or forced out of the plane of said metal sheet, so that they will extend downwardly into the several pockets or compartments formed by the intersecting wires 11, and engage upon the intersecting upper and lower wires as clearly shown in Fig. 2 of the drawings. This metal sheet 12 has adhesively or otherwise secured thereto at spaced points, or between the series of spring tongues 14, the intersecting strips of felt 15. There is enough slack or looseness in these felt strips where they cross the pockets or compartments to permit the same to sag downwardly into said compartments and rest against the inclined spring tongues 14 as is also clearly shown in Fig. 2. At the intersecting points of these strips, a disk of rubber, cork or other suitable material indicated at 16 is secured, and upon this disk the smaller end of the egg indicated at E directly engages or rests.

The case sections 5 are hingedly connected together at one of their ends as shown at 17, and the construction of the egg supporting frames carried by each section is identical with that above described. It will be understood that after the carrier frames 30 have been secured upon or to the boundary walls 6, the cover member 7 is secured in place. Angular metal bracing plates 18 are preferably applied to the corners of the case and secured to the walls 6 and cover member 7 to rigidly connect and brace the same. The corner plates 18 on the case sections are preferably formed at one of their ends as shown in Fig. 14 to form a half joint when the case is closed. After the eggs have been 35 arranged in either section of the case, as shown in Fig. 2, the other case section is folded over upon that section containing the eggs. The upper larger ends of the eggs will thus be received between the wider 40 strands of wire constituting a part of the carrier frame in the latter case section. It will be obvious that by the provision of the resilient frame wires together with the spring tongues 14, and the pliable or elastic intersecting felt strips 15, an extremely 45 yieldable cushion or support is provided for the eggs so that after the case sections have been locked or otherwise securely fastened together, any rough handling of the case 50 will not dislodge the eggs from their several positions so that they will engage with each other and be broken, nor can the eggs move to a sufficient extent to engage the base 55 boards 8 of the cover sections 7 of the case 60 sections with sufficient force to break the 65

eggs. It will thus be seen that I have devised a practical, highly serviceable and convenient carrier for the shipment of eggs and like fragile commodities.

In Figs. 4, 5 and 6, I have disclosed a 70 slightly modified form of the invention which is somewhat simpler than that above described. In this construction, it will be observed that each case section 5' is provided adjacent its open side with a single 75 series of intersecting wire strands 11', forming a rectangular carrier frame. In this construction, the wire frame is not secured directly to the walls of the case but the corners of said frame are connected to the 80 corners of the case interiorly thereof by means of the elastic bands 19. Over the intersecting wires of the frame, the plate 12' of aluminum or other sheet metal is adapted to be arranged, said plate being 85 provided with series of resilient tongues 14' in a similar manner to the preferred form of the invention, said tongues extending downwardly through the spaces or compartments defined by the intersecting wires 11'. 90 The intersecting felt bands 15' are also employed in this form of the invention with which the eggs or other articles immediately contact. As shown in Fig. 5, at the right and left hand sides thereof, when the case 95 is empty, the apexes of the spring tongues 14' are contiguously disposed so that they define substantially a conical cup or pocket. When however, an egg is placed in one of these pockets, the weight thereof forces the 100 opposing spring tongues 14' in opposite directions and stretches the intersecting flexible bands 15' extending across said pockets. These bands support the egg out of direct contact with the metal tongues and 105 obviate all possibility of the eggs being broken during shipment. It will be observed from this description that the principal difference between this form of the device and that shown in Fig. 1, resides 110 in the fact that the egg receiving carrier frame is yieldably suspended in the case and is not permanently secured upon the case walls. In connection with this latter form of the invention, I also contemplate substituting for the intersecting strips of felt or other fabric 15', a continuous felt sheet which is disposed over the wire frame. In Fig. 6 I have illustrated a fragment of this felt sheet, the same being designated by the 115 numeral 20, and it will be observed that the sheet is cut or slotted over its entire area as at 21 to produce a plurality of diamond shaped tabs 22 which are integrally connected to each other at their central and widest 120 points as shown at 23. This fabric sheet is secured at its edges to the boundary wire of the carrier frame and the diamond shaped tabs 22 are adapted to extend downwardly upon each side of the intersecting 125 130

wires and upon the opposite spring metal tongues 14', one half of the same tab 22 engaging upon the contiguous tongues of adjacent pockets or compartments.

5 In Fig. 7 of the drawings, I have illustrated a suspending spring 24 for the wire carrying frame which may be employed in lieu of the elastic strips 19.

Referring now to Figs. 8 and 9 of the drawings, which disclose a further modification of the essential characteristics of my invention, 25 designates an aluminum or sheet metal plate, which plate is formed with a series of triangular shaped outwardly punched spring tongues 26 arranged diametrically opposite to each other. It is to be particularly observed that in this modified construction, the tongues 26 are considerably smaller than the tongues 14 and 14' disclosed 15 in the previously referred to forms of the device. Between the tongues 26, the triangular sections of metal are cut out as indicated at 27 and upon the upper surface of the sheet of aluminum 25, a sheet of felt or other resilient material 28 is secured. This sheet of felt is also cut to provide diametrically opposed triangular shaped tabs 29 which are slightly larger than the spring metal tongues 26 and adapted to lie upon 20 and entirely cover the same. The felt between the tabs 29 is cut out to provide spaces between the tabs corresponding to the open spaces 27 in the metal plate 25. In addition to the felt sheet 28, the intersecting felt 25 strips 30 are provided, said strips being adhesively or otherwise secured to the sheet 28 and extending into the egg receiving pockets or compartments upon the triangular shaped tabs 29 of the sheet of felt. These intersect-

30 strips 30 are also provided at their points of intersection with the supporting disks of cork or other yieldable material indicated at 31. To each corner of the metal plate 25, one end of a coil spring 32 is attached, the other ends of the springs being secured to the respective corners of the case. From this construction, it will be apparent that in the provision of the felt sheet 28, which overlies the spring metal tongues 26, 35 I have provided an additional cushioning medium for the eggs, so that breakage thereof will be rendered absolutely impossible, in the handling of the shipping crate or case.

In Fig. 10 of the drawings, I have disclosed still another modified form of the invention wherein the egg supporting frame is yieldably suspended within the case body, by the vertically disposed spring plates 37 which are fixed at their lower ends to the 40 blocks 38 secured in the corners and centrally at opposite sides of the case. The upper ends of these plates are notched or recessed as clearly shown at 39, to detachably receive the headed ends of the rods 40 which are loosely connected at their other

ends to the carrier frame. It will be obvious that by suspending the frame within the case body in this manner, when the case is subjected to violent shock or jar, the frame together with the fabric strips are free to move with respect to the case walls, and in such movement, the spring plates 37 are bent or bowed inwardly from their normal positions, said plates effectually preventing the frame from striking the sides of the case, so that no pressure whatever will devolve upon the eggs.

5 In Fig. 11 I have shown a further modification of the means for suspending the article receiving frame, wherein the aluminum or other sheet metal plate 57 is provided at each of its corners with a cylindrical stud 58. Expansion springs 59 are engaged at one of their ends over these studs, the other ends of said springs being suitably secured to the corners of the case or carrier as shown.

Referring now to Fig. 12 wherein I have shown an additional suspension means for the plate 57, 62 designates a U-shaped bracket plate which is secured to the inner faces of the side and end walls of the case. Between the inwardly extending parallel arms of this U-shaped bracket plate a cushioning block of cork, rubber or other yieldable material shown at 63 is arranged. These cushioning blocks are provided with notches or recesses 64 to receive the edges of the article supporting plate 57.

6 In Fig. 13 of the drawings, still another suspending means for the sheet metal or aluminum plate is illustrated, wherein it will be observed that the opposed ends of vertically arranged pairs of expansion springs 65 are fixed to the edge of the plate, the other ends of the springs being secured to the wall of the case. In addition to these springs, a wood block or cleat 66 is movably mounted upon the under side of the plate by means of the screw 67. A strip of cork or other cushioning material 68 is secured to the lower edge of said cleat for contact with the base or bottom wall of the case while to the upper edge thereof a similar cork strip 69 is adhesively or otherwise secured. Between this latter strip of cork and the under face of the article supporting plate a strip of rubber or other relatively soft yieldable material 70 is interposed. This arrangement of these springs 65 and the blocks or cleats 66 with the cushioning means therefor is arranged centrally at each of the end and side edges of the article carrying plate.

7 From the foregoing description taken in connection with the accompanying drawings, it is thought that the construction, manner of use and several advantages of the different forms of my invention which I have deemed it advisable to illustrate, will be fully and clearly understood. It will

be obvious from such description that the invention is capable of still further modification in various respects, and while I do not specifically refer to the same, all alternative forms which might be fairly construed as embracing the essential characteristics of the device are contemplated in putting the invention into practical use. A shipping crate or case for frangible commodities constructed in accordance with my invention is highly efficient and serviceable in practical use as it eliminates all liability of breakage which in the case of eggs frequently results in considerable monetary loss to the shipper. However, it is of course manifest that the invention may be utilized with the adoption of slight modifications for the transportation of various other articles of commerce with the same advantageous results. It is also apparent that the crates or cases may be constructed in various forms and sizes to suit the particular circumstances of their use and that the frames for yieldably suspending the articles may be constructed of other material than wire. It is therefore to be understood that the invention is susceptible of various other modifications than those above disclosed in the form, proportion and arrangement of the several elements and I reserve the privilege of resorting to all such legitimate changes as may be fairly embodied within the spirit and scope of the invention as claimed.

Having thus described the invention, what is claimed is:

1. In an article carrier of the character described, the combination with a case, of a metal frame arranged in said case and provided with a plurality of series of downwardly projecting resilient tongues which constitute the walls of article receiving pockets, and flexible intersecting strips secured at intervals to the frame and loosely extending at their intersecting points into the several article receiving pockets and adapted under the weight of an article to be distended beyond the free ends of said tongues.

2. In an article carrier of the character described, the combination with a case, of spaced series of horizontally extending intersecting wires arranged within said case to form a plurality of article receiving pockets, a metal plate supported by one series of intersecting wires and having a plurality of series of spring tongues cut therefrom and extending into the respective pockets, said tongues engaging at their free ends upon the other series of intersecting wires,

and intersecting fabric strips secured upon said plate and loosely extending at their points of intersection over the spring tongues and into the several pockets, said intersecting strips under the weight of an article engaged thereon being distended beyond the free ends of the tongues.

3. In a carrier of the character described, the combination with a case, of spaced series of intersecting wire strands arranged in said case to form a plurality of article receiving pockets, and a metal plate arranged upon one of said series of wire strands and having a series of spring tongues cut therefrom and extending into each of said pockets, said tongues engaging at their free ends with the wire strands of the other series to yieldingly support the articles in the pockets.

4. In a carrier of the class described, the combination with a case, of spaced series of intersecting wire strands threaded through the walls of the case, the parallel strands of one series being arranged in closer relation to each other than the corresponding parallel strands of the other series to form a plurality of article receiving pockets, a metal plate arranged upon the latter series of wire strands and having spring tongues cut therefrom and extending into said pockets and engaging at their free ends upon the first named series of wire strands, and flexible cushioning material arranged over each of said tongues upon which the article is adapted to rest.

5. In a carrier of the class described, the combination with a case, of spaced series of intersecting wire strands threaded through the walls of the case, the parallel strands of one series being arranged in closer relation to each other than the corresponding parallel strands of the other series to form a plurality of article receiving pockets, a metal plate arranged upon the latter series of wire strands and having spring tongues cut therefrom and extending into said pockets and engaging at their free ends upon the first named series of wire strands, and intersecting fabric strips secured at intervals to the upper surface of said plate, said strips at their points of intersection extending into the respective pockets and yieldable cushioning disks secured to the intersecting points of said fabric strips.

In testimony whereof I hereunto affix my signature in the presence of two witnesses.

ALLEN J. COUGHENOUR.
